Wm B. Phillips. Design for Stone. Patented July 25. 1846.

Fig. 1.

Fig. 2.

Wells and Sonning Co.

Ezra Ripley, Troy, N. Y.

Letters Patent Design No. 73, dated 25 July 1846
ante-dated 28 May 1846

The Schedule referred to in these Letters Patent and making part of the same.

To all to whom these presents shall come:

Be it known, that I, Ezra Ripley of Troy in the County of Rensselaer and State of New York, have invented or produced a new design for a stove, and that the following is a full, clear and exact description of the same, reference being had to the accompanying drawings, making part of this Specification, in which figure 1 is a view of the top plate, and figure 2, the side plate. The same letters indicate like parts in all the figures.

This design consists of a gothic pattern, the upper part of the side of which is formed of quatre foil in circular recesses as shown in the drawing at (2). On each side near each corner are three compartments (b) of tracery work in imitation of three windows one above the other, and in the centre between them is a large door shaped compartment (c) divided into two vertically by scroll work (d) flanked by gothic pinnacles (e); on each side the ground work between the bars is all formed in diamond work all of which will more clearly appear by the drawing accompanying this description in fig. 2.

The top of this design is oblong having a square compartment (f) in the centre with indented corners at each end of which is another compartment (g) ornamented with line and leaf work; and on each side are compartments (h) formed of leaf ornament these compartments project beyond the line of the stove as shown in the drawing, the corners are filled with a honeysuckle pattern and the space between ^{the} is occupied with a quatre foil (i) in a die.

I claim as my design for stoves the above described and illustrated pattern and desire to secure the same by Letters Patent.

A. P. Brown { witness,
J. J. Greenough

Ezra Ripley
